CLAIM

The ornamental design for a hook rack, as shown and described.

DESCRIPTION

FIG. 1 is a front, side and top perspective view of a hook rack showing our new design;
 FIG. 2 is a front elevational view thereof;
 FIG. 3 is a top plan view thereof;
 FIG. 4 is a side elevational view thereof;
 FIG. 5 is a bottom plan view thereof;
 FIG. 6 is a rear elevational view thereof;
 FIG. 7 is front, side and top perspective view of a second embodiment of a hook rack in accordance with our new design, showing a two hook style;
 FIG. 8 is a front elevational view thereof;
 FIG. 9 is a top plan view thereof;
 FIG. 10 is a side elevational view thereof;
 FIG. 11 is a bottom plan view thereof; and,
 FIG. 12 is a rear elevational view thereof.

The broken-line disclosure of elements in the views is for illustrative purposes only and forms no part of the claimed design.
